GARAGE DOOR

William M. Winans, Monrovia, Calif.

Application October 14, 1938, Serial No. 235,052

4 Claims. (Cl. 268—50)

This invention relates to door operating means and more particularly to such means applied to garage doors and the like.

An object of the invention is to provide a simple, practical and inexpensive mechanism for opening and closing garage doors and the like.

Another object is to provide a mechanism of the character described adapted for actuation at a distance from the door and conveniently located within reach of a driver of a motor vehicle while seated therein.

Another object is to provide a mechanism of the character described having incorporated therein novel locking means.

Other objects and advantages will appear and be brought out more fully in the following specification, reference being had to the accompanying drawings wherein.

Fig. 1 is a view in elevation of a doorway illustrating my invention applied thereto.

Fig. 2 is a top view of the same.

Fig. 3 is a side view of the same.

Fig. 4 is a view in elevation of an operating arm.

Fig. 5 is a plan view of the same.

Fig. 6 is an enlarged side elevation of the same.

Fig. 7 is an end view of the operating handle.

Fig. 8 is a sectional view taken along the line 8—8 of Fig. 6 and

Fig. 9 is an enlarged view illustrating a portion of the locking means.

Referring more particularly to the drawings, I show a wall portion 10 of a building such as a garage or the like having a doorway 11 and a door 12 having two or more supporting brackets 13, each carrying a roller 14 adapted to have rolling engagement with track 15 suitably mounted on wall 10. A lazy tong mechanism 16 is secured as by a bar 17 to bracket 13 and is provided with a guide roller 18 which also rides on track 15. A pair of cylinders 19 and 20 are supported as by brackets 21 to wall 10 and receive the ends of a piston 22 which is reciprocable therebetween.

A pin 23 is secured to piston 22 and to the intersecting pivot of a pair of the lazy tong arms and a pin 24 secures the end of the lazy tongs to cylinder 20. A pipe 25 connects cylinder 19 with a cylinder 26 and a pipe 27 connects cylinder 20 with a cylinder 28, cylinders 26 and 28 being mounted in a suitable housing 29 adapted to be placed in the ground adjacent the driveway leading to the garage.

A piston 30 is reciprocable between cylinders 26 and 28. An upstanding hollow rod or pipe 31 is connected by suitable fittings 32 to piston

30. A pipe section 33 has a sleeve 34 secured thereto, sleeve 34 being slidable over the upper end of pipe 31. The opposing ends of pipes 31 and 33 are sutured to form a clutch and a spring 35 is suitably positioned therein to normally keep the pipes separated. A lever arm 36 is secured by an elbow 36a to pipe 33 and may be provided with a suitable handle 37.

Door 12 is provided with a lock piece 38 adapted for interfitting engagement with a lock piece 39 mounted on wall 10 and a lock bar 40 is slideable in a bracket 41 on door 12 and is connected at its upper end to a link 42 secured to the end of a stiff wire or cable 43 in pipe 27, the other end of wire 43 terminating in housing 29 and being connected to a tubular member 44 mounted in bearing piece 45 on cylinder 28. Tubular member 44 has a square bore into which a squared rod 46 is slidably positioned.

A gear 47 is secured to rod 46 within fitting 20 32 and a gear 48 which meshes with gear 47 is secured to the lower end of a wire or flexible cable 49 which extends through pipes 31, 33 and lever 36. A suitable armored tube 50 or the like is secured in elbow 36a to prevent twisting of wire 49 during operation.

A lock 51 is mounted in handle 37 and is connected to the end of wire 49. Pipes 25 and 27 and cylinders 19, 20, 26 and 28 are filled with oil. To prevent leakage of the same, suitable packing glands 52 are secured to the ends of pipe 27 where the ends of wire 49 extend therethrough.

The operation of the invention should be apparent from the foregoing description. Handle 37 is grasped and a downward pressure thereon and on lever 36 will engage the clutch and forward movement thereof will cause piston 30 to create a pressure on the oil in cylinder 28 which is transmitted through pipe 27 to cylinder 20 causing a movement of piston 22 which in turn will be transmitted to pin 23 and lazy tongs 16 causing the latter to expand and opening the door 12. A reverse movement of lever 36 and piston 30 will create oil pressure in cylinder 26, pipe 25 and cylinder 19 which will be transmitted to piston 22 and lazy tongs causing the latter to contract, thus closing the door 12. Previous to the opening of the door, lock rod 40 will have been released from lock member 38 by a key in lock 51 which, when turned, turns wire 49 which turning movement is transmitted through gears 48 and 47 and rod 46 and tube 44 to wire 43 which is connected to link 42, the latter being connected to rod 40. Similarly, after closing the door, the key in lock 51 will by reverse movement, 55

cause rod 40 to lock members 38 and 39. The spring 35 which separates pipes 31 and 33 permits lever 36 to be swung out of the way when not in use and if accidentally struck by a motor vehicle, it would swing out of the way and prevent injury to the same.

It will be understood that the foregoing description is illustrative rather than restrictive of the invention and that changes and modifications may be made without departing from the spirit and the scope of the subjoined claims, for instance: The relative size of cylinders 19, 20, 26 and 28 as well as the length of pistons 22 and 30 may be varied in practice as may be required to meet various actual conditions, such as different weights and sizes of doors, taking into account the force necessary to move them.

Having described my invention, what I claim is:

1. A mechanism of the character described, comprising a door suspended from an overhead track, a pair of spaced cylinders parallel to said track, a piston within the cylinders and spanning the space between the same, a fluid pressure system for operating the piston in said cylinders for moving the piston in opposite directions, lazy tongs connected at one end to the door and its opposite end connected to one of the cylinders, a pin carried by the piston and connected to one of the pivots of the lazy tongs, and a fluid pressure system operating the piston, whereby the movement of the piston opens and closes the door.

2. A mechanism of the character described,

comprising a door suspended from an overhead track, a cylinder parallel to said track, a piston in said cylinder, lazy tongs having one end connected to the door and the opposite end connected to the cylinder and having a roller traveling on said track, an arm connecting one of the pivots of the lazy tongs with the piston, and fluid pressure for operating the piston.

5

3. A mechanism of the character described, comprising a door suspended from an overhead track, a cylinder parallel to said track, a piston in said cylinder, lazy tongs having one end connected to the door and the opposite end connected to the cylinder and having a roller traveling on said track, an arm connecting one of the pivots of the lazy tongs with the piston, and a remote control fluid pressure system for operating said piston.

10

4. A mechanism of the character described, comprising a door suspended from an overhead track, a pair of spaced cylinders parallel to said track, a piston within the cylinders and spanning the space between the same, a fluid pressure system for operating the piston in said cylinders for moving the piston in opposite directions, lazy tongs connected at one end to the door and its opposite end connected to one of the cylinders, a pin carried by the piston and connected to one of the pivots of the lazy tongs, a fluid pressure system operating the piston, and a remote hand operated piston in the fluid pressure system for operating the pistons for operating the lazy tongs.
